US00D602650S

(12) United States Design Patent
Garcia-Lucio et al.

(10) Patent No.: US D602,650 S
(45) Date of Patent: * Oct. 20, 2009

(54) HUMMINGBIRD FEEDER

(76) Inventors: Alfredo Garcia-Lucio, 135 W. 1st. Ave., Denver, CO (US) 80223; Jim B. McKeever, 135 W. 1st. Ave., Denver, CO (US) 80223

() Term: 14 Years

(21) Appl. No.: 29/305,105

(22) Filed: Mar. 13, 2008

(51) LOC (9) Cl. 30-03

(52) U.S. Cl. D30/124

(58) Field of Classification Search D30/121, D30/124–128, 110, 115, 117, 119; 119/51.01, 119/57.8, 53, 428, 429, 469
